COMBINED MICROPHONE AND CALLING MAGNETO

Michel Louis Oules, Vélizy, France

Application November 21, 1957, Serial No. 48,583

Claims priority, application France May 22, 1957

Term of patent 14 years

(Cl. D26—14)

FIG.2

Fig. 1 is a rear perspective view of a combined microphone and calling magneto, showing my new design with the hinged protective cover in open position; and

Fig. 2 is a front perspective view thereof.

The broken line fragmentary showing of a connecting cord is for illustrative purposes only.

I claim:

The ornamental design for a combined microphone and calling magneto, as shown and described.
